Des. 194,700

Patented Feb. 26, 1963

194,700

COMBINED SALT AND PEPPER SHAKER OR SIMILAR ARTICLE

Frank L. Telerico, 120 McMonagle Ave., Pittsburgh, Pa.

Filed Jan. 18, 1962, Ser. No. 68,368

Term of patent 7 years

(Cl. D44—22)

Fig. 1

Fig. 2

Fig. 3

Fig. 5

Fig. 4

FIGURE 1 is a front elevation view of a combined salt and pepper shaker or similar article showing my new design;

FIGURE 2 is an edge elevational view thereof;

FIGURE 3 is a top plan view thereof;

FIGURE 4 is a sectional view on line IV—IV of FIGURE 3; and

FIGURE 5 is a perspective view taken from the side opposite to that of FIGURE 1.

The essential features of my design are shown in full lines.

I claim:

The ornamental design for a combined salt and pepper shaker or similar article, substantially as shown and described.
